UNITED STATES PATENT OFFICE

152,602

DESIGN FOR A DISPLAY FIXTURE

Edwin C. Dimling, Flushing, N. Y., assignor to
Cluett, Peabody & Co., Inc., Troy, N. Y., a cor-
poration of New York

Application July 27, 1946, Serial No. 132,012

Term of patent 14 years

(Cl. D80—9)

To all whom it may concern:

Be it known that I, Edwin C. Dimling, a citizen of the United States, residing at Flushing, Queens County, New York, have invented a new, original, and ornamental Design for Display Fixtures, of which the following is a specification, reference being had to the accompanying drawing, forming part thereof.

In the drawing:

Fig. 1 is a perspective of a display fixture, showing my new design;

Fig. 2 is a front elevation thereof;

Fig. 3 is one end elevation thereof;

Fig. 4 is the opposite end elevation thereof; and

Fig. 5 is a plan of the same.

I claim:

The ornamental design for a display fixture, substantially as shown.

EDWIN C. DIMLING.
